H. D. BARTLETT.
COAL HANDLING DEVICE.
APPLICATION FILED FEB. 21, 1921.

1,423,986.

Patented July 25, 1922.

UNITED STATES PATENT OFFICE.

HARRY D. BARTLETT, OF CHICAGO, ILLINOIS.

COAL-HANDLING DEVICE.

1,423,986.

Specification of Letters Patent. Patented July 25, 1922.

Application filed February 21, 1921. Serial No. 446,560.

To all whom it may concern:

Be it known that I, HARRY D. BARTLETT, a citizen of the United States of America, and a resident of Chicago, county of Cook, 5 and State of Illinois, have invented certain new and useful Improvements in Coal-Handling Devices, of which the following is a specification.

The main objects of this invention are to 10 provide an apparatus for handling coal for domestic use; to provide an improved form of hopper; to provide mechanism for vertically shifting the hopper in a supporting frame; to provide means for locking said 15 mechanism to hold the hopper in certain elevated positions; to provide an improved form of follower for urging the coal along the bottom of the hopper toward the outlet opening; to provide means for actuating 20 said follower and simultaneously controlling the passage of coal through said opening; and to provide means for weighing the hopper and its contents.

An illustrative embodiment of this invention is shown in the accompanying drawings, in which—

Figure 1 is a side elevation of the device, showing the hopper in its elevated position.

Fig. 2 is a rear elevation.

Fig. 3 is an enlarged fragmentary detail, partly in section, showing the chute and follower.

Fig. 4 is an enlarged detail showing the catch for holding the winch in its operative 35 position.

In the form shown, the apparatus comprises a supporting frame 1 having arranged therein a hopper 2 which is vertically shiftable by means of a winch 3 whereby the hopper is elevated to a position where its contents may be readily discharged by gravity 40 through the firing door of a furnace or other heating plant.

The frame 1 comprises a plurality of 45 upright supporting members 4 in the form of angle irons providing guideways for the vertically shiftable hopper. Secured at the lower end of the frame, and disposed at right angles, is an axle 5 and a bar 6 carrying respectively supporting wheels 7 and casters 8 which permit the apparatus to be conveniently trundled between the coal bin and the heating plant. Extending across the upper end of the frame is a brace 9 having suspended therefrom a centrally located 55 weighing scale 10 which is provided with a

hook 11 for engaging a bracket 12 extending across the top of the hopper, whereby the latter may be supported by the scale independently of the hoisting sling when it is 60 desired to weigh the fuel.

The hoisting sling comprises a flexible cable 13 having one end secured to the upper end of the supporting frame at one side of the device. The running part of the sling is 65 in sliding engagement with pulleys 14 journaled at the lower end of the hopper and the other end of the cable is fastened to the winch 3. The winch is journaled in brackets 15 and 16 mounted on the opposite side of 70 the frame and is provided with a crank 17 extending rearwardly and located within convenient reach of the operator. The winch is longitudinally shiftable in its bearings and is held in its outer or operative position, 75 as shown in Figure 1, by an angle-shaped catch 18 which is pivotally connected to the bracket 16 so as to be adapted to bear between the bracket and a pipe union 19 of the winch. To secure the winch in its inoperative 80 position for retaining the load in an elevated position a lug 20 is secured to one of the uprights 4 and projects outwardly from the frame in position to engage the crank. 85

The hopper is formed with a bottom which is inclined downwardly and forwardly of the apparatus to form a chute 21 extending through an outlet opening 22 formed in the front wall of the hopper. The lower part 90 of the chute projects beyond the front wall of the hopper and is provided with side walls 23. Mounted in the lower end of the chute is a hinged gate 24 which is shiftable to control the passage of fuel through 95 the projecting section. The gate is provided with side flanges 25 so that when the gate occupies its open position it forms a continuation of the chute.

Pivotedly mounted on a bracket 26 extending across the rear wall of the hopper is a lever construction which comprises a pair of levers 27 connected at their upper ends by a handle 28. The lower ends of the levers are connected to the side flanges 25 of the 105 gate by links 29 located one on each side of the hopper.

To assist the coal in its initial movement through the outlet opening, a channel-shaped follower 30 is slidably arranged in the chute 110 and connected to the flanges 25 by links 31 so as to be operated by the gate through the

action of the lever 27. The upper edges of the side flanges of the follower slidably engage pins 32 extending inwardly from the lower walls of the hopper. Extending transversely across the bottom of the follower are ridges 33 which provide shoulders for pushing the coal toward the outlet. A push rod 34 is slidably arranged in the chute above the bottom of the follower and extends 10 through the rear wall of the hopper so that the rod may be shifted back and forth for agitating the coal when the gate is open.

In operation, the apparatus is filled at the coal bin and when a supply is needed for 15 the heating plant the device is trundled to a position directly in front of the firing door. The winch is then operated to elevate the hopper to the desired position so as to permit the lower section of the chute to project 20 into the fire box. To hold the hopper in its elevated position the catch 18 is lifted to permit the winch to be shifted forwardly in its bearing to bring the crank 17 in front of the lug 20. When the winch occupies this position 25 the weight of the hopper urges the crank into engagement with the adjacent upright member 4 which secures the handle against rotation. The lever 27 is then operated to shift the gate to its open position 30 and the forward movement of the gate simultaneously actuates the follower 30 to assist the fuel in its initial movement through the outlet. When the lever 27 is operated to 35 close the gate, the follower is shifted back to its normal position. If it is desired to weigh the contents of the hopper, the winch is operated to elevate the hopper to the upper end of the supporting frame so as to 40 permit the suspended hook of the scale to engage the bracket 12.

Although but one specific embodiment of this invention is herein shown and described it will be understood that numerous details of the construction shown may be altered or 45 omitted without departing from the spirit of this invention as defined by the following claims.

I claim:

1. A device for handling coal comprising 50 a supporting frame having a hopper slidably mounted therein, mechanism carried by said frame for vertically shifting said hopper, the bottom of said hopper being inclined to form a chute having an outlet at 55 one side of said frame, a hinged gate mounted in said outlet and arranged to form a continuation of said chute, means for shifting said gate into position to close said outlet, and a follower slidably arranged in said 60 chute and connected to said gate so as to be actuated thereby.

2. A device for handling coal comprising a supporting frame having a hopper slidably mounted therein, mechanism carried by said 65 frame for vertically shifting said hopper,

the bottom of said hopper being inclined to form a chute having an outlet at one side of said frame, a hinged gate mounted in said outlet and arranged to form a continuation of said chute, a lever pivotally mounted 70 on said frame and connected to said gate for shifting said gate into and out of position to close said outlet, a second chute arranged within said first mentioned chute to form a follower, and a link connecting said fol- 75 lower and gate.

3. A device for handling coal comprising a supporting frame having a hopper slidably mounted therein so as to be vertically shiftable, a winch carried by said frame, a sling 80 supporting said hopper and having sliding engagement therewith, one end of said sling being secured to the upper end of said frame, the other end of said sling being secured to said winch, the bottom of said hopper being 85 inclined to form a chute having an outlet at one side of said frame, a hinged gate mounted in said outlet and arranged to form a continuation of said chute, means for shifting said gate into and out of position to 90 close said outlet, and a follower slidably arranged in said chute and connected to said gate so as to be actuated by said gate through the operation of said means.

4. A device for handling coal comprising 95 a supporting frame having a hopper slidably mounted therein so as to be vertically shiftable, a winch journaled in brackets carried by said frame for operating said hopper, a crank carried by said winch, said winch 100 being longitudinally shiftable in said brackets to bring said crank into engagement with said supporting frame for securing said winch against rotation, the bottom of said hopper being inclined to form a chute hav- 105 ing an outlet at one side of said frame, a hinged gate mounted in said outlet and ar- ranged to form a continuation of said chute, means for shifting said gate into and out of position to close said outlet and a follower 110 slidably arranged in said chute and connected to said gate so as to be actuated by said gate through the operation of said means.

5. A device of the class described com- 115 prising a chute, a hinged gate mounted in the outlet of said chute, and a follower slidably arranged in said chute and connected to said gate so as to be actuated thereby.

6. A device of the class described com- 120 prising a chute having an outlet at one end thereof, a hinged gate mounted in said out-let and arranged to form a continuation of said chute, a second chute arranged within said first mentioned chute to form a fol- 125 lower, and a link connecting said follower and gate.

Signed at Chicago this 18th day of February 1921.

HARRY D. BARTLETT.
